UNITED STATES PATENT OFFICE.

GEORGE RYAN FLYNN, OF LOWELL, MASSACHUSETTS.

CALCULATING DEVICE.

1,426,829.

Specification of Letters Patent. Patented Aug. 22, 1922.

Application filed April 8, 1921. Serial No. 459,617.

To all whom it may concern:

Be it known that I, GEORGE RYAN FLYNN, a citizen of the United States, residing at Lowell, in the county of Middlesex and State 5 of Massachusetts, have invented certain new and useful Improvements in Calculating Devices, of which the following is a specification.

This invention relates to calculating devices, particularly that type which is small and compact so that it can be carried in the pocket or in a small circular case.

This device is especially useful for students, but includes various scales and formulæ useful for surveyors, mechanical engineers, and others who have occasion to figure out mathematical problems.

It is so arranged that most of the calculating devices are of semi-circular form and 20 can therefore be read directly without turning. This is particularly true of that part of my device which includes a semi-circular slide rule, and I believe that I am the first to devise such a rule.

In the drawings, Fig. 1 is a front view or 25 elevation of my preferred form of device, including a semi-circular slide rule, angle formulæ, sine tables, and protractor.

Fig. 2 is an elevation, being a view from 30 the right of Fig. 1.

Fig. 3 is a view of the top part of the base as it appears without the marks for sine tables.

Fig. 4 is an elevation on a smaller size 35 than Fig. 1 of the base with the half disc member and runner removed.

Fig. 5 is a view of a modified form of base in the form of a perfect disc, but with the degrees for the protractor scale omitted, as 40 well as the sine tables, but having the angle formulæ and the slide rule scales.

Fig. 6 is an elevation showing a modified form of my device which embodies the semi-circular slide rule alone.

In Figs. 4, 5 and 6, the actual markings 45 are in some cases merely indicated, as it is believed this makes for clearness.

In the drawings, A represents a base made of any suitable sheet material in the form 50 substantially of two half discs, the upper half disc 10 having its diameter line 18 extending between the points 11 and 13 and coinciding with the edge of a slot 17 cut in the base. The point X in the diameter line 18 is 55 the center of half disc 10.

Around the outside, from the point 11 to

12, is a scale showing degrees, and from 12 to 13 a continuation of the same scale showing degrees, the whole being in semi-circular form. Inside the degrees scale, arranged 60 concentrically in semi-circular form, are the scales 8, 9, 14 and 15, showing co-tangents, sines, co-sines, and tangents. These are preferably staggered so that the radial lines 16, 65 16, running through the scales to the degrees, will not confuse, but will permit the various scales to be read more easily.

The lower half of base A, 20, is substantially semi-circular, with its center point at Y, which is below the point X of the upper 70 part. On this lower part, as clearly shown in Fig. 4, are the semi-circular slide rule scales 23, 24 and 26, also the angle formulæ readings 21 and 22. These angle formulæ readings continue between the two parts of 75 A at 19, as shown.

With pivot point Y as a center, half disc member B is revoluble on base A. The pivot may comprise a headed member 43 and washer 44, which serves as a pivot for B and 80 runner C.

Half disc member B has an inside open slot H of semi-circular form arranged so that the markings 23 will come along one edge, while it is marked at 34 with a slide 85 rule scale. The outer edge of half disc B is cut away to form an outside slot G cut in such position as to expose the slide rule scale 24, the adjoining curved edge of B being marked with a slide rule scale 35. 26 is 90 the other marking for a slide rule scale which shows through slot G. The part K of half disc member B between the slots H and G thus serves as a semi-circular slide rule member. 95

Cut through half disc member B are the slots 30, 31, 32, to expose the readings on the angle formulæ scales 19, 21, 22, on base A.

Pivoted on pivot point Y is a transparent runner C which extends out over the edge of 100 B and A, as shown at 41 and 42 in Fig. 2. This is marked with a hair line 40 which crosses the slide rule scales and is used to assist in reading them.

As shown in Fig. 3, the upper part 10 of 105 the base A may be simply marked with the degrees, leaving out the sine tables, the rest of the device being the same as shown in Figs. 1 and 4. In this case the combination consists of the slide rule, angle formulæ 110 and protractor.

As shown in Fig. 5, the base P may be a

perfect disc, with its upper half 50 without degrees scale or sine table markings, but having the slide rule markings 23, 24, 26 and the angle formulæ markings 19, 21, 22. This 5 forms the combination of the semi-circular slide rule and the angle formulæ.

As shown in Fig. 6, base R may be a perfect disc with its upper part 60 free from markings of any kind, but with its lower 10 half having the slide rule markings 23, 24, 26, and the half disc member S pivoted at the pivot point Y having the inside slot H, outside slot G and the semi-circular slide part K between them, having the slide rule 15 markings 34 and 35. This arrangement forms a semi-circular slide rule alone.

I claim:

1. In a calculating device, the combination of a base having a straight-edged slot 20 with a straight edge which coincides with the diameter line for a series of scales arranged concentrically in semi-circular form, the outside scales showing degrees and the inside scales showing the corresponding 25 sines, co-sines, tangents and co-tangents, and a pivot point on a second center, together with scales arranged in semi-circular form with said pivot point as a center showing the markings of one member of a slide rule 30 and other markings arranged in a semi-circular form with reference to said pivot point showing angle formulæ, with a half disc member revoluble on said pivot so cut as to expose the slide rule markings of the base 35 so as to form a semi-circular slide member of the slide rule with markings thereon and having apertures in proper relation to read the angle formulæ, together with a transparent runner pivoted on said pivot and 40 having a hair line which crosses the slide rule scales.

2. In a calculating device, the combination of a base having a slot with a straight edge in which is the center point of a semi- 45 circular scale and a pivot point which is at

another center for semi-circular slide rule scales and a curved angle formula scale marked on said base, with a half disc member pivotal on said pivot point so cut as to form a semi-circular slide member with 50 scales thereon for the slide rule and with apertures to disclose the angle formula scale, together with a transparent runner pivotal on said pivot point having a hair line which crosses the slide rule scales. 55

3. In a calculating device, the combination of a base having a slot with a straight edge in which is the center point of a semi-circular scale, and a pivot point which is at another center for semi-circular slide rule 60 scales and another scale marked on said base, with a half disc member pivotal on said pivot point so cut as to form a semi-circular slide member with scales thereon for the slide rule and with apertures to disclose the other scale, together with a transparent runner pivotal on said pivot point having a hair line which crosses the slide rule scales. 65

4. In a calculating device, the combination of a base having a pivot point for a semi-circular slide rule scale and another scale, with a half disc member pivotal on said pivot point so cut as to form a semi-circular slide member with scales thereon 70 for the slide rule and with apertures to disclose the other scale, together with a transparent runner pivotal on said pivot point having a hair line which crosses the slide rule scales. 75

5. In a calculating device, the combination of a base having semi-circular slide rule scales and a pivot point therefor, with a half disc member with slide rule scales, pivotal on said pivot point so cut as to form 80 a semi-circular slide member for the slide rule and a transparent runner pivotal on said pivot point having a hair line which crosses the slide rule scales. 85

GEORGE RYAN FLYNN.
